TOWER GRILLAGE

Filed Feb. 5, 1929

Inventor:
GEORGE F. PORTER,
by *Usina & Lauber*
Atty's

UNITED STATES PATENT OFFICE

GEORGE F. PORTER, OF DETROIT, MICHIGAN; DETROIT TRUST COMPANY, OF DETROIT, MICHIGAN, EXECUTOR OF SAID GEORGE F. PORTER, DECEASED

TOWER GRILLAGE

Application filed February 5, 1929. Serial No. 337,667.

This invention relates to grillages or footings for the legs of transmission towers or the like, and more particularly to a novel means for attaching and supporting said legs in 5 position on said grillage.

Heretofore, the lower end of the tower legs have generally been flattened and inserted between two channel members as shown and described in the Leeper Patent No. 1,180,592, 10 dated April 25, 1916. The construction of the Leeper patent is objectionable since there is an angle between the flattened end of the leg, which is vertical, and the remainder of the tower leg which is disposed at an angle. 15 Due to this angle between the flattened lower end of the tower leg and the remainder of the leg, there is a tendency for the leg to push the channels, between which its lower end is inserted and secured, over sidewise so that they 20 tend to revolve about their bases, and the leg bends in the juncture between the flattened portion and upper angle portion causing a failure of the tower leg.

The present invention has for its object the 25 provision of a novel mounting for the tower legs which entirely eliminates the objections noted above, is cheaper to make, and provides a materially stronger construction.

In the drawings:

30 Figure 1 is an elevation showing the lower end of a transmission tower embodying my invention.

Figure 2 is an enlarged fragmentary sectional plan showing the tower leg attaching means and taken on the line II-II of 35 Figure 3.

Figure 3 is an enlarged fragmentary side elevation showing the tower leg mounted in the grillage.

40 Figure 4 is a plan of the grillage.

Figure 5 is a fragmentary elevation of one corner of the grillage.

Referring more particularly to the drawings, the letter A designates the tower structure as a whole, the lower portion only being shown. The tower A is of an ordinary and well known construction and consists of leg portions 2 of angle sections, which legs are provided with separate lower sections 3 45 termed stub-angles. The lower leg sections or

stub-angles 3 are mounted in the grillage or footing B.

The legs 2 are connected to form a rigid structure by cross-bracing composed of laterals 4 and diagonals 5 in the usual manner.

This invention is directed to the footing or grillage B for the tower legs and it will, therefore, be understood that I do not wish to be limited to any particular tower construction.

The footings or grillages to which the stub-angles or lower leg sections 3 are secured are mounted in suitable holes in the ground and the holes may be filled with concrete or earth, as desired. The grillage consists of a plurality of cross-ties or other suitable bearing members 7 arranged parallel with each other in spaced relation, a pair of connecting angle members 8 extending at right angles to the longitudinal axis of the ties 7 adjacent their ends and fixedly secured thereto by rivets or bolts, and a pair of channel beams or other shapes 9 are mounted intermediate the ends of the ties in parallel spaced relation with each other and at right angles to the longitudinal axis of the ties 7. The beams 9 are secured to the top faces of the ties 7 by bolts or rivets 9^a and are spaced a sufficient distance to permit the mounting of the ends of the stub-angles or lower tower leg sections 3 between said beams.

The lower ends of the tower legs, which are of angle sections, have the outer portions of their flanges or edges bent at an angle of 45 degrees, as at 10, so as to extend at right angles to the vertical faces of the beams 9. The bent portions 10 of the lower ends of the tower legs are connected by an angular center portion 12 which adds stiffness to the structure.

The lower ends of the tower legs are adapted to be secured to the beams 9 by right angled attaching plates 14. A pair of the plates 14 are secured to the inside vertical face of each of the beams 9. The plates 14 are arranged on an angle equal with the angular position of the tower legs with their backs opposite each other and spaced a distance equal to the thickness of the tower legs so as to permit 400

the portions 10 of the legs to fit snugly there-between.

Suitable bolts or rivets 15 are used to secure the plates 14 to the beams 9 and to secure the tower legs to the plates.

The present construction entirely eliminates the weak spot located at the flattened portion of the prior art structure and, therefore, the tower leg will not kink or bend. The bent portions 10 of the tower leg are adapted to be bent cold while the flattened ends of the prior art structure were necessarily heated and forged, a much more expensive operation.

15 The new structure permits the channels 9 to be spaced farther apart than the channels of the prior art structure, whereby the movement on the grillage beams is greatly reduced, and either their size may be reduced with a 20 consequent saving in cost or they may be extended a greater distance and more bearing area secured for the grillage.

25 While I have shown and described one specific embodiment of my invention, it will be understood that I do not wish to be limited thereto, since various modifications may be made without departing from the scope of my invention as defined in the appended claim.

30 I claim:

35 The combination of a footing having spaced channel sections positioned with their backs opposite each other and extending vertically and a tower leg which in vertical section is oblique to said footing, said leg having its ends between said backs of said channels and having in cross-section an angular center bounded by edge portions which are in line with each other and at right angles to the backs of said channels, and right angle plates 40 secured to the backs of said channels on the opposite sides of said edge portions of said leg and in line with said leg for splicing said edge portions of the leg to said channels.

45 In testimony whereof, I have hereunto set my hand.

GEORGE F. PORTER.
